UNITED STATES PATENT OFFICE.

ALBERT D. KENESTON, OF ALBANY, NEW YORK, ASSIGNOR TO GEORGE KENESTON, OF SAME PLACE.

INKING MECHANISM FOR MULTICOLOR-PRINTING.

SPECIFICATION forming part of Letters Patent No. 639,247, dated December 19, 1899.

Application filed July 20, 1897. Serial No. 645,212. (No model.)

To all whom it may concern:

Be it known that I, ALBERT D. KENESTON, a citizen of the United States, residing at Albany, in the county of Albany and State 5 of New York, have invented new and useful Improvements in Inking Mechanism for Multicolor-Printing, of which the following is a specification.

My invention relates to mechanism for distributing on an inking-roller inks of two or 10 more colors for use for multicolor-printing; and it consists of the novel construction and combinations of the devices and elements hereinafter described, and pointed out in the 15 claims.

The objects of my invention are to provide a printing-press with a simple mechanism which may be readily applied to the press for distributing two or more color-inks simultaneously on the same inking-cylinder; also, to provide mechanism by which the two or more color-ink rollers may be automatically moved longitudinally and reciprocatingly in contact with the same ink-distributing 20 roller, and, further, to provide mechanism by means of which the length of reciprocating longitudinal movement of the two or more ink color rollers may be adjusted at the will of the operator, as may be predetermined.

Other objects and advantages of this invention will be fully understood from the following description and claims, when taken in connection with the annexed drawings, in 35 which—

Figure 1 is a side elevation of a printing-press (a suitable portion thereof shown) having my invention applied thereto. Fig. 2 is a view taken in transverse section at line 1 in 40 Fig. 1, with parts shown in section. Fig. 3 is a sectional view taken at line 2 in Fig. 1. Fig. 4 is a view of opposite end, taken at same line 2 in Fig. 2. Fig. 5 is a plan view of the ink-roller-shaft keeper; and Fig. 6 is a section taken at line 3 in Fig. 5.

Like letters of reference refer to like parts throughout the several views.

The drawings show so much of a printing-press of the kind known to the trade as the 50 "Universal" as is deemed necessary for illustrating a press to which my invention may

be applied. In the drawings, in this press, A is a portion of the frame of the press.

B is the revolving ink-cylinder.

C is the revolving crank-disk, mounted on 55 the drive-shaft of the press, and D is the pitman intermediate between the crank-disk C and the platen, which latter and other parts of the press are not shown, their illustration being unnecessary for a full understanding 60 of my invention.

E is a longitudinal reciprocating shaft having mounted thereon two or more color-ink-distributing rollers F, adapted each to freely revolve independent of the others, yet simultaneously. This shaft E is cylindrical in form and of suitable thickness for stiffness and of length to include portion e between the bearings a a in the frame, and a suitable extension, as e', projected outward beyond 70 one of said bearings a for reception of the reacting spring G, while the opposite end is provided with a suitable engaging device—say as hook E'—for holding the cord or chain, hereinafter described. The outer end of portion e' is provided with the spring-keeper e², which may be made of any suitable form and secured to said end by a pin or screw.

H H are shaft-keepers suitably secured to the frame-pieces A at points adjacent the 80 bearings a a for service as upper side bearing-pieces for preventing shaft E from rising from the bearings a. My preferred means for securing these keepers in place consists of a binding-bolt H', provided with nut H². 85 Although the form of these shaft-keepers may be varied, yet I prefer to make their bodies h with an oblong form and each with a width corresponding with that of the slots a', leading to the bearings a and provided 90 with lateral flanges h', Figs. 3, 4, 5, and 6, for bearing on the edge margin sides of slots a', as shown in Figs. 3 and 4, while their lower ends are each provided with notch h³ for service as an upperside bearing of shaft E. These 95 shaft-keepers are set in slots a' in the frame and have their bearing ends h³ at such a distance from the bottoms of bearings a as to hold said shaft from rising and at the same time allow it to be freely moved longitudinally in 100 either direction.

The color-ink-distributing rollers F are

preferably made of elastic composition, as generally employed by the trade, and are each mounted on an independent tubular shaft F', which is itself mounted on shaft E, so as to 5 freely revolve thereon. Adjustable thimbles F², provided each with set-screw f, are also provided on shaft E and are employed one at each end of each distributing-roller F, as shown in Fig. 2, for keeping the two or more 10 of these rollers at their predetermined distance apart on shaft E. These ink-distributing rollers F F are employed in numbers corresponding with the number of color-inks to be distributed on the inking-cylinder B, 15 whether two, three, or any other preferred number.

I, Figs. 2 and 4, is a spring-guard arranged over the reacting spring G and shaft portion e'. This guard I is preferably made with an 20 inverted-U form in its cross area for inclosing the upper and lateral sides of said spring G and the portion e' of shaft E within said spring. This guard I is preferably integral with bracket I', which is adapted to 25 have its body portion i fit in slot a', leading to bearing a, while lateral flanges i² are provided for bearing against the outer side edge margins of the said slot, as shown in Fig. 4, while the binding-bolt H', preferably secured 30 to its adjoining shaft-keeper, rigidly secures said bracket with the frame at the same time said bolt secures the adjoining shaft-keeper in place.

J, Figs. 1 and 2, is a friction-roller bracket 35 secured to the side frame opposite that to which the spring-guard I is secured. This bracket may be of any suitable form and be secured by any suitable means with such side frame, so as to adapt it to hold the friction- 40 roller K in position with its peripheral groove on a line with the axis of shaft E for carrying a draft cord or chain from the engaging hook F' to a suitable connecting-link, as will be hereinafter described. This bracket J has 45 its attaching portion J' fitting in slot a' and provided with flanges j j for bearing against the outer edge margins of said slot and also with a perforation for receiving the binding-bolt H', by which this bracket is secured to 50 the frame.

L is a link adjustably connected with link-keeper M, which may be pivotally connected with the pitman D or any other suitable reciprocating piece directly or indirectly, as 55 may be preferred. This link L is provided at its upper end with a loop or hook l for engagement with a flexible connection between said link and the shaft E, and it is provided below with a screw-threaded binding screw or 60 bolt l', provided with nut l².

The link-keeper M is made with an oblong slot m and with guiding-flanges m' m', between which flanges the body of the adjustable link is held by the binding device l' when 65 said link has been adjusted longitudinally in relation to its keeper.

The link-keeper M may be pivoted directly

with the pitman D in some presses, while in other presses it may be pivoted to some other reciprocating or moving device or part of the 70 press or attachment thereto without departing from the spirit of this invention. When applied to the press of the class above mentioned, I prefer to clip pivot N to pitman D by means of clip O, made sectional and of 75 parts o o', held together by binding-screws o² o², with one of the parts, as o, having pivot N integral with it, so that said pivot may be readily applied at will to said pitman D at any preferred point in the length thereof, as 80 may be found to be advantageous or most convenient. This pivot N receives the eye M', shown to be provided on the lower end of the link-keeper M, which is secured thereon by means of nut N', screwing on the screw- 85 threaded stem n, made with pivot N.

P is a flexible draft connection between link L and shaft E and is connected by one of its ends with hook or loop l of the said link and by its opposite end with the device or 90 hook F' of the said shaft E, while the body of this draft connection is carried by the friction-roller K. This draft connection P may be made of cord or chain, as may be preferred, and is guarded at the friction-roller by loop q 95 of keeper Q, arranged at a suitable point over roller K, so as to allow the cord or chain to freely move through loop q and is held in place by the perforated limbs q' q' of said keeper Q and the pivot-pin k, passing through 100 the ears of the bracket J and friction-roller K.

When the above-described devices and parts are applied to the press, as above described, the adjustable link L will be adjusted in relation to its keeper M for lengthening or 105 shortening the distance between pivot N and the flexible draft connection P for regulating the length of the longitudinal movement to be given to shaft E, which movement may there- 110 by be varied from one-half of an inch to two inches or more, as may be preferred or be 115 found to be advantageous for best results, and the higher link L is raised in the keeper above the pivot N the shorter will be the length of the movement of the shaft, while a 120 lowering of the said link will effect a corresponding lengthening of such movement, and whether the movement of the shaft E be longer or shorter the flexible draft connection 125 P will be more or less slack, and the length of its slack will be increased as the length of the movement of said shaft is decreased and be lessened when the movement of the latter is to be increased.

In operation the downward pull of the connection P will move the shaft E and the several inking-rollers thereon longitudinally in one direction to the distance allowed by the adjustment of the link L in relation to its keeper M. Then the reacting spring G will 130 operate to move said shaft and inking-rollers longitudinally in the reversed direction. In both these longitudinal movements of said shaft and inking-rollers thereon the latter

will revolve in contact with the inking-cylinder B and transfer to it its proper proportion of colored ink, as before predetermined shall be distributed on said cylinder.

5 Having described my invention, what I claim, and desire to secure by Letters Patent, is—

1. The combination with the ink-cylinder of a printing-press and slot-form bearings *a a* 10 in the side frames of the same, of the longitudinally-reciprocating shaft E adapted to serve as a spindle on which an inking-roller may be mounted, of a reacting spring between one end of said shaft and an end of the bearing adjoining said spring, a link secured to a moving part of the press and adapted to have a reciprocating movement, a flexible draft connection between the opposite end of said shaft and said link, and a friction-roller supporting the body of said flexible draft connection, substantially as and for the purposes set forth.

2. In a printing-press, the combination with a longitudinally-reciprocating shaft which 25 serves as a spindle on which two or more ink-rollers revolve for distributing ink to an ink-cylinder, a pivot secured to a moving portion of the press, of a link which vibrates from said pivot, a flexible draft connection between said reciprocating shaft and said link, a friction-roller carrying the body of said flexible connection, and a reacting spring between the opposite end of said shaft and the end of the bearing adjoining said 35 spring, substantially as set forth.

3. In a printing-press, the combination with the frame-pieces A, provided with slot-form bearings, a reciprocating shaft, supported in said bearings, and shaft-keepers H H' having 40 their bodies entered into the slot-form bearings and provided with lateral flanges *h*', of devices J' and I' and binding-bolts H' H' binding devices J' and I' to their respective adjoining shaft-keepers, substantially as and 45 for the purposes set forth.

4. In a printing-press, the combination with the reciprocating shaft E supported in slot-form bearings provided in the frame-pieces A, and a spring between one end of said shaft 50 and the outer end of the bearing adjoining said spring, of a spring-guard having its bracket portion I' provided with lateral flanges *i*', a shaft-keeper H provided with flanges *h*' and binding bolt H' and nut substantially as set 55 forth.

5. In a printing-press, the combination with the reciprocating shaft E, supported in slot-form bearings, a friction-roller provided with a peripheral groove, a bracket J supporting said 60 roller at a distance from one end of said shaft and with its groove on a line with the axis of the latter and having its portion J' provided

with flanges *j*, of a draft connection P between said shaft E and a moving part of the press and a shaft-keeper H provided with flanges *h*' and the binding-bolt H', substantially as and for the purposes set forth.

6. In a printing-press, the combination with the pitman D, a pivot secured to said pitman, a sectional slotted link, having its parts adjustable lengthwise so as to be adapted to be lengthened and shortened at will, secured to said pivot, a reciprocating shaft supported in bearings and an ink-cylinder supported parallel with said shaft, of a draft connection 70 between said shaft and link, a friction-roller supporting said draft connection and a reacting spring at the opposite end of said shaft, substantially as and for the purposes set forth.

7. In a printing-press the combination with 80 a reciprocating moving part of the press, a sectional clip provided with binding-screws adapting said clip to be adjusted on said moving part, a pivot connected with one section of said clip, a sectional link adapted to be lengthened and shortened, and working on said pivot, of an ink-roller, a reciprocating shaft parallel with said ink-roller, a flexible connection between said link and one end of the said shaft, and a spring reacting against the pull of 90 said flexible connection on the said shaft, substantially as and for the purposes set forth.

8. In a printing-press, the combination with an ink-roller, a reciprocating shaft arranged parallel to said roller, a pitman, a sectional 95 clip which is adjustable on said pitman and provided with a pivot on one of its sections, a link, adapted to be lengthened or shortened at will, working on said pivot, of a flexible draft connection between said link and one 100 end of said shaft and a reacting spring at the opposite end of said shaft, substantially as and for the purposes set forth.

9. In a printing-press the combination with the reciprocating shaft E a friction-roller, a 105 bracket supporting said roller, a vibrating draft-link and a flexible draft connection between said link and said shaft, of keeper Q, provided with loop *q*, arranged over the portion of the draft connection on the crown of 110 said roller and supported from said bracket, substantially as and for the purposes set forth.

10. In a printing-press, the combination of the ink-cylinder, the sectional ink-distributing roller, the platen-operating rod, a connection between one end of the roller and the rod whereby the roller is moved endwise in one direction by the rod, and a spring at the other end of the roller whereby the latter is moved endwise in the opposite direction.

ALBERT D. KENESTON.
